Primary Examiner — Holly H Bayham(74) *Attorney, Agent, or Firm* — FisherBroyles, LLP;
Jason M. Pass(57) **CLAIM**

I claim the ornamental design for a wallet, as shown and described.

DESCRIPTION

A portion of the disclosure of this patent document contains material to which a claim for copyright is made. The copyright owner has no objection to the reproduction of the patent document or the patent disclosure, as it appears in the U.S. Patent Office records, but reserves all other copyright rights whatsoever.

FIG. 1 is a front perspective view of a wallet, according to my design.

FIG. 2 is a front view of the wallet of FIG. 1;

FIG. 3 is a rear view of the wallet of FIG. 1;

FIG. 4 is a top view of the wallet of FIG. 1;

FIG. 5 is a bottom view of the wallet of FIG. 1;

FIG. 6 is a right side view of the wallet of FIG. 1;

FIG. 7 is a left side view of the wallet of FIG. 1; and,

FIG. 8 is a left front perspective view of the wallet of FIG. 1.

The broken lines shown in the drawings illustrate portions of the wallet that form no part of the claimed design.
